CLAIM

The ornamental design for a wireless speaker with a mirror, as shown and described.

DESCRIPTION

FIG. 1 is a perspective view of a wireless speaker with a mirror showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and

FIG. 7 is a left side elevational view thereof;

FIG. 8 is a front perspective view thereof showing the mirror in an alternate position; and,

FIG. 9 is a rear perspective view thereof, showing an attachment device removed and the support member in an alternate position.
